UNITED STATES PATENT OFFICE.

EDWARD C. HAVER, OF CHAMBERSBURG, PENNSYLVANIA, ASSIGNOR TO JAMES A. HAVER, OF CHAMBERSBURG, PENNSYLVANIA.

BOILER BLOWER.

Application filed April 24, 1919. Serial No. 292,440.

To all whom it may concern:

Be it known that I, EDWARD C. HAVER, a citizen of the United States, residing at Chambersburg, in the county of Franklin and State of Pennsylvania, have invented certain new and useful Improvements in Boiler Blowers; and I do hereby declare the following to be a full, clear, and exact description of the invention, such as will enable others skilled in the art to which it appertains to make and use the same.

The present invention relates to boiler blowers particularly adapted for cleaning the flues of a fire tube boiler of the horizontal type, and has for an object to provide an improved and efficient blower adapted to sweep across the open ends of a plurality of the tubes and which is capable of movement for selectively supplying fluid under pressure into desired groups of the tubes.

Another object is to provide a boiler blower of this type which is capable of adjustment toward and from the adjacent ends of the boiler tubes for varying the area over which the fluid under pressure strikes the tubes for the purpose of concentrating the fluid under pressure into desired tubes and for varying the effective pressure of the blower against the tubes.

A further object is to provide a boiler blower which is capable of manual adjustment and operation for sweeping the desired tubes or area of the tubes at the adjacent end of the boiler.

With these and further objects in view as will in part hereinafter become apparent and in part be stated, the invention comprises certain novel constructions, combinations and arrangements of parts as subsequently specified and claimed.

In the accompanying drawings,—

Figure 1 is a side elevation, partly in section, of a fire tube boiler mounted in a furnace and showing the application of the present preferred embodiment of the invention thereto.

Figure 2 is a front end elevation of the boiler and furnace showing the boiler blower attached thereto and illustrating in dotted lines several positions into which the nozzle arm may be swung.

Figure 3 is a detail, enlarged, vertical section taken through the adjustable bearing

and journal on substantially the line 3—3 of Figure 1.

Figure 4 is a horizontal section taken through the same substantially on the line 4—4 of Figure 3.

Referring to the drawings by numerals, 10 designates a fire tube boiler of the horizontal type having the usual steam dome 11 and mounted in a furnace 12. The furnace is provided with a front wall 13 adapted to support the flue blower of this invention, and is provided in the usual manner with the front doors 14, admitting access to the front of the boiler.

The front wall 13 carries a transverse bar or brace 15 preferably of angle iron construction secured at opposite ends against the inner side of the front wall 13 and extending across the door opening thereof at a point slightly below the longitudinal axis of the boiler 10. A guide plate 16 is mounted upon the intermediate portion of the brace 15 and extends inwardly toward the boiler 10, and has a dove tail recess or way 17 in its upper face extending longitudinally of the plate 16 and adapted to receive a correspondingly shaped tongue 18 depending from a bearing block 19. The bearing block 19 is of any suitable configuration and is adapted to slide longitudinally over the upper face of the plate 16, the block 19 being provided with a rod 20 which extends forwardly through the front wall 13 and is pivoted to the lower end of a hand lever 21.

The hand lever 21 has, intermediate its ends, a longitudinal slot 22 through which projects a pivot pin 23 carried upon the forward end of a supporting rod 24. The pin 23 is adapted to pivotally support the lever 21 and the slot 22 admits of longitudinal shifting of the lever 21 as the latter is moved into various positions of adjustment for sliding the block 19 toward and from the front of the boiler 10. A segment 25 is supported upon the front wall 13 and is adapted to be traversed by the lever 21, a locking dog 26 being employed for securing the lever 21 in its various adjusted positions.

The rod 24 is threaded at its inner end and passes through the front wall 13, and is provided at opposite sides of the front wall with lock nuts 27 adapted to hold the rod 24 rigid.

As may be best seen from Figures 3 and 4, the block 19 is provided with a longitudinal axial opening 28 for receiving a hollow journal 29 held from shifting longitudinally 5 from the block 19 by stop collars 30 and 31 held in place by set screws or the like. The collar 31 has a closed end wall and supports a shaft 32 which is co-axial with the hollow journal 29 and secured thereto for rotating 10 the same. The shaft 32 projects forwardly through the wall 13 and is provided with a sprocket wheel 33 over which is trained an endless chain 34 adapted to be suspended on the sprocket wheel and to be operated 15 manually for turning the hollow journal 29. The block 19 is provided, intermediate its ends, with an enlarged annular groove or recess 35 adapted to register at all times with a series of openings or ports 36 formed 20 in the side walls of the journal 29 to establish communication between the interior of the block 19 and the interior of the journal 29. Preferably, the block 19 is provided on its top with a cap plate 37 having a threaded 25 opening therein communicating with the annular groove 35 and adapted to receive a pipe 38 which rises from the block.

Upon the inner end of the journal 29 is threaded an elbow 39 carrying a radially 30 extending distributing arm 40, the elbow and the arm having a longitudinal row of outlet nozzles 41 facing the front end of the boiler 10. The arm 40 is hollow and capped on its free end and the nozzles 41 communicate 35 with the interior of the arm for spraying the fluid under pressure which is fed into the arm. The arm 40 is adapted to swing with its journal 29 in the block 19, and is of sufficient length to sweep the entire surface 40 area of boiler tubes at the front of the boiler. In order to facilitate the adjustment of the arm 40 into various positions, as shown in dotted lines in Figure 2, the arm 40 carries a co-axially extending rod 42 45 which projects beyond the opposite side of the journal 29, and carries an adjustable counterbalancing weight 43. The weight 43 may be adjusted upon the rod 42 for counterbalancing the arm and for thus maintaining 50 it in any desired position to swing.

For the purpose of introducing fluid under pressure into the block 19 and the parts connected thereto, the dome 11 of the boiler is tapped with a pipe 44 having a valve 45 55 therein close to the dome 11, and which extends forwardly over the furnace 12 to a position beyond the front wall 13. The pipe 44 is carried down in front of the wall 13 at one side of the door opening, as shown 60 in Figure 2, and is connected by a U-coupling 45 to a return pipe 46 which rises against the front wall 13 to a point near the top of the boiler and is thence carried through the front wall and provided with 65 a ball and socket coupling 47. The pipe

38 which rises from the block 19 is provided with a second ball and socket coupling 48, and a pipe 49 connects the two ball and socket couplings 47 and 48, and includes an expansion joint 50 admitting of variations 70 in the length of the pipe 49 incident to the shifting of the block 19 on the supporting plate 16. The ball and socket joints 47 and 48 admit of variations in the angular relation between the pipe 49 and its adjacent pipes 46 and 38.

The feed pipe 44 is provided near its lower end, and a short distance above the U-coupling, 45, with a hand valve 51 for shutting off supply of the fluid under pressure to 80 the pipe 46, and is provided with a drain pipe 52 connected to the pipe 44 immediately above the valve 51 and which leads to the ash-pit of the furnace 12. A hand valve 53 is placed in the pipe 52 near its juncture 85 with the pipe 44. A drain cock 54 is preferably placed in the bottom of the U-coupling 45 for draining the return pipe 46 after the valve 51 has been closed.

In use, the valve 45 is opened to admit 90 steam through the pipe 44, and the valve 51 is opened to admit the steam into the pipe 46 and into the block 19. During the operation, the valve 53 is closed as well as the pet cock 54. The steam passing from the 95 pipe 46 is forced through the coupling 47, the expansion joint 50, the second coupling 48, and into the block 19. The steam, or other fluid under pressure, enters the annular groove 35 which constitutes the chamber within the block, and finds access to the hollow journal 29 through the ports or openings 36. These ports or openings 36 are preferably elongated narrow slots extending 100 lengthwise of the journal and are in sufficient number to freely admit the fluid under pressure to the journal. The fluid passes through the journal 29 and elbow 39 into the arm 40 and is ejected through the outlet nozzles 41 toward the forward ends 110 of the boiler tubes. As shown in Figure 1, when the block 19 is retracted toward the front wall 13, the fluid under pressure sprays from the nozzles 41 and strikes the forward end of the boiler 10 in a relatively wide surface area throughout the 115 length of the arm 40 and consequently the force of the fluid under pressure is dissipated to some extent. This Figure 1 also shows, in dotted lines, the block 19 advanced toward the boiler 10 and shows the relatively small surface area of the front of the boiler which is covered by the projected streams of fluid. Naturally, when the arm 40 is advanced toward the boiler, greater 120 force of the fluid is projected into the boiler tubes with the desired result of dislodging accumulations thereof, such as when first starting to blow out the blower. The hand lever 21 is manipulated to position the block 125

130

19 at the desired distance from the boiler and may be shifted from time to time during the cleaning operation, the hand lever being locked by the dog 26 in adjusted position.

5 The chain 34 is operated by hand for swinging the arm 40 with its journal 29 to cover the entire surface area of the front of the boiler and to bring the nozzles 41 into 10 the desired positions in front of the boiler tubes. When it is desired, the arm 40 may be maintained stationary at any suitable point of revolution so as to concentrate the fluid under pressure toward and into any 15 desired group of the boiler tubes.

To facilitate the removal of soot and accumulations from the upper part of the boiler shell a branch pipe 55 extends from the main steam pipe 44 preferably in front 20 of the wall 13 of the furnace, and is provided with a hand valve 56 to control passage of fluid under pressure through the pipe 55. The pipe 55 is then carried back through the wall 13 and across the inner 25 side of the wall to a position immediately over the boiler 10. The pipe 55 is provided near the front end of the boiler with a four-way coupling 57 having lateral branches to which distributing arms 58 are connected, 30 the arms 58 being arcuate in form and adapted to lie closely against the boiler shell. Rearwardly projecting nozzles 59 are carried by the branch distributing pipe 58 and the latter extends down to the sides of 35 the boiler. Distributing pipe sections 60 are connected to one another and to the pipe 55 by union couplings 61, and each is provided with the four-way coupling 57 and its branch distributing pipes 58 and nozzles 59. There is thus a spraying device arranged at the forward and rear ends of the boiler and at the intermediate portion thereof, and it is, of course, understood that any 40 desired number of these spraying devices may be employed. The pipe 60 which is located intermediate the ends of the boiler is arcuate or curved laterally to pass around the steam dome 11, as shown in Figure 1. The pipes 55 and 60 are adapted to rest 45 upon the boiler shell and are held in place not only by their couplings but also by the distributing arms or sections 58 which engage the sides of the boiler.

The segment 25 and the post 24 of the 55 manual control means for advancing and retarding the rotary distributor in front of the boiler are arranged upon one of the front doors 14 and are adapted to be swung away from the boiler when the door is 60 opened after the rod or link 20 has been disengaged from the lower end of the hand lever 21, as shown in Figure 2. The link 20 passes between the meeting edges of the doors 14 when the latter are closed and the 65 doors may have notches 62 therein for ac-

commodating the rod or link 20. A detachable pin or any other suitable element may be used to connect the rod 20 with the lever 21.

I claim:

1. In a boiler blower, the combination, with a support adapted to be mounted adjacent a boiler, of a reciprocally mounted block carried by said support and movable toward and away from the boiler, a tube 75 swivelled in the block, the block being formed with a groove and the tube with an aperture communicating with the groove, the said swivelled tube having a distributing arm positioned to lie parallel to the adjacent portions of the boiler so as to extend across the tubes thereof, the distributing arm being adapted to swing on the swivel for successively moving across substantially all of the tubes of the boiler, the said arm having discharge nozzles directed toward the boiler, means for supplying fluid under pressure to the groove of the block, a lever for shifting the block to various adjusted positions while leaving the distributing arm free to swing on the swivel, means for locking the lever in such adjusted positions, and means for actuating the distributing arm.

2. In a boiler blower, the combination, with a support adapted to be mounted adjacent a boiler, of a reciprocally mounted block carried by said support and movable toward and away from the boiler, a tube swivelled in the block, the block being formed with a groove and the tube with an aperture communicating with the groove, the said swivelled tube having a distributing arm positioned to lie parallel to the adjacent portions of the boiler so as to extend across the tubes thereof, the distributing arm being adapted to swing on the swivel for successively moving across substantially all of the tubes of the boiler, the said arm having discharge nozzles directed toward the boiler, means for supplying fluid under pressure to the groove of the block, a locking segment mounted adjacent to and spaced from the mounting of the block support, a lever having a pawl engaging the segment for locking the lever in various positions, and a link 100 connecting the lever to the block for shifting the block without interfering with the action of the distributing arm.

3. In a boiler blower, the combination, with a support adapted to be mounted adjacent a boiler, a reciprocally mounted block carried by said support and movable toward and away from the boiler, the said block having a dove-tail joint with said support for holding the block against lateral and vertical displacement and permitting reciprocation thereof, a tube swivelled in the block, the block being formed with a groove and the tube with an aperture communicating with the groove, the said swivelled tube 115 120 125 130

having a distributing arm positioned to lie parallel to the adjacent portions of the boiler so as to extend across the tubes thereof, the distributing arm being adapted to swing on ¹⁰ the swivel for successively moving across substantially all of the tubes of the boiler, the said arm having discharge nozzle directed toward the boiler, and means for supplying

fluid under pressure to the groove of the block.

In testimony whereof I affix my signature in presence of two witnesses.

EDWARD C. HAVER.
